UNITED STATES PATENT OFFICE.

FREDERICK C. POTTER, OF NEW YORK, N. Y.

DESIGN FOR A WALL-BRACKET.

SPECIFICATION forming part of Design No. 36,117, dated October 21, 1902.

Application filed September 9, 1902. Serial No. 122,743. Term of patent 14 years.

To all whom it may concern:

Be it known that I, FREDERICK C. POTTER, a citizen of the United States, and a resident of the city of New York, borough of Manhattan, in the county and State of New York, have invented a new, original, and ornamental Design for a Wall-Bracket, of which the following is a full, clear, and exact description.

Reference is to be had to the accompanying drawings, forming a part of this specification, in which similar characters of reference indicate corresponding parts in both the figures.

Figure 1 is a front elevation of a wall-bracket, showing my design; and Fig. 2 is a side elevation of the same.

The design in its entirety consists of an open-work back A, from the lower portion of which extends forwardly the vertical open-work brace B, on which rests the solid shelf C, the said back A appearing composed of an open compass D, from the apex of which rises a cable ring E, containing the letter "G" and surrounded by small ornaments E', the ring E resting at its sides on the globes F, capping the columns G, the bases of which appear flush with the top of the shelf C, postaments H, with open books I thereon, flanking the said columns, the lower portion of the back A appearing with a square J within a

pendant K in the form of a semicircular cable wreath, from which rise a hammer L and a spade N, which cross each other and intersect the legs of the square J and the legs of the compass above the shelf C, a trowel O 35 appearing at the crossing of the spade and hammer and the conventional representation of a heart P appearing at the apex of the square J and the lower portion of the pendant K, the said brace B appearing with an anchor 40 Q within a triangle R.

The leading feature of the design consists in the representations of the insignia emblematic of the Masonic order and the representation being arranged and united, as 45 shown, to form the back and brace of the bracket.

Having thus described my invention, I claim as new and desire to secure by Letters Patent—

The ornamental design for a wall-bracket as herein shown and described.

In testimony whereof I have signed my name to this specification in the presence of two subscribing witnesses.

FREDERICK C. POTTER.
